PROCESS AND APPARATUS FOR MAKING FINGER RINGS

Filed Jan. 6, 1925

INVENTOR

Clifford W. Allsopp
BY
Fred C. Fischer
ATTORNEY

UNITED STATES PATENT OFFICE.

CLIFFORD W. ALLSOPP, OF NEWARK, NEW JERSEY.

PROCESS AND APPARATUS FOR MAKING FINGER RINGS.

Application filed January 6, 1925. Serial No. 775.

This invention relates to the manufacture of finger rings or engraved bands of like nature, the invention including a novel process as well as an apparatus for performing portions of the same.

One of the features of the invention is in the provision of means for producing rings which are alike and of uniform weight regardless of finger size.

Another object is to provide means by which a definite design can be uniformly produced at a far less expense than can be done by hand chasing.

A further aim is in the production of rings of unusual durability, including the chased design, due to condensing and hardening of the metal during the process of ring construction.

These and other valuable features, such as reduction in cost of manufacture, speed of production and superior excellence of product, are accomplished by the novel methods and mechanism hereinafter described and illustrated in the accompanying drawing, forming an important part of this disclosure, and in which:—

Figure 1 is a partial front elevational, partial vertical sectional view of an embodiment of the ring rolling apparatus.

Figure 2 is a transverse sectional view of the same.

Figure 3 is a plan view of a plain ring of substantially cylindrical cross section.

Figure 4 is a like view of an engraved ring made from another of the same series of blanks.

Figure 5 is a similar view showing a ring of larger diameter made from another blank of the same series.

In carrying out the process of ring making by the present disclosure, a metal, as platinum, gold or the like is rolled into a strip or bar substantially equivalent to the desired width of the finished ring, this strip being subjected to dies in a power punch press to produce washers of rectangular cross section.

These blanks are relieved of their sharp corners, both internally and externally, and struck between dies which give them approximately the shape they will eventually have and bring them to a uniform thickness, after which they are skimmed clean on the inside and outside, ready for rolling which will be further on described.

After rolling, the rings may be stamped

on their inside, as with the karat mark, trademark, et cetera, rounded up, stripped, the design touched up by hand, again skimmed, millgrained on the edges and finished by 60 buffing and polishing preparatory for the market.

Referring now to the drawing, the numeral 10 designates the base of a rigid frame having right and left sides, respectively 11 and 12, and an integral front wall 13 on which is a cylindrical boss 14 extending inward from the wall 13 and also outward beyond the edge of the base 10.

A pair of transverse bosses 15 extend upward from the base 10, the same being in register with an outstanding lug 16 on the side wall 11, these bosses and lugs being bored to receive a shaft 17, to the outer extending end of which is rigidly attached a hand lever 18 provided with a detent 19, the point of which is engageable in one of a series of notches 20 formed in a sector 21 secured to the foundation of the machine.

Between the bosses 15, the shaft 17 has formed on it an eccentric 22 rotatable in a sleeve 23 from which extend upwardly a pair of arms 24, each containing circular openings 25 and having at their upper ends inturned bosses 26 carrying a pin 27 on 80 which is pivotally mounted a link 28.

This link is bifurcated at its opposite end and engaged in the fork thereof, by the pin 29, is a rib 30 extending centrally down from a table 31 having down-turned right angled plate flanges 32 fitted to slide vertically between the sides 11 and 12 of the main frame.

Thus it will be seen that the table 31 may be raised or lowered by the hand lever 18 95 in a relatively rapid manner.

The table may also be actuated by means of a pair of eccentrics 33, operating in the openings 25 of the arms 24, entirely independent of the hand lever.

The eccentrics 33 are keyed or otherwise secured to a shaft 34, mounted in bearings 35 on the side walls 11 and 12, and is provided with collars 36 to prevent end movement of the shaft, which has rigidly secured at its center a worm wheel 37.

Enmeshed with the wheel 37 is a worm 38 fixed on the end of a spindle 39 mounted in the boss 14 and having on its outer end a hand wheel 40, by the operation of which the table may be raised or permitted to lower.

Arranged above the machine is a housing 41 positively rigid with respect to the machine, and mounted in the housing is a shaft 42, carrying a roll 43 between the forks of 5 the housing, this roll having an annular recess 44, the bottom of which is engraved as at 45.

A pair of supports 46 are raised from the table 31, these supports being spaced slightly apart and having recesses in their upper 10 edges, directly over the axis of the shaft 17 and pivot pin 31, the recesses being receptive of the ends 47 of an arbor 48 of such diameter as to readily pass through a ring 15 49, to register with the groove 44 of the master roll 43.

It will now be seen that upon lowering the table by the hand lever 18, the ring and arbor may be instantly removed and a plain, 20 untreated ring substituted for one on which the rolling operation has been completed, and it is to be noted that the pressure applied to the ring stretches and increases the diameter in exact ratio to its extent.

25 The pressure is thus varied in accordance with the results to be attained and calibrated by means of a register 50, the stem 51 of which is actuated by a bar 52, rigidly fixed in the table flange to extend through an elongated opening 53 in the frame side 30 12, the register being supported by an arm 54 fixed firmly to the same side frame.

Thus, a ring blank having been placed on the arbor, the table is raised so that the blank engages in the master roll and to a 35 point shown on the indicator as correct for the specific size of the ring desired, the raising being accurately and easily accomplished by the hand wheel 40, which moves the lever arms 24 and pivot 27.

40 During the process of rolling, which is very rapid, the metal is stretched and condensed to become measurably hardened and entirely without waste making all rings, made from the same sized blanks, uniform in weight, notwithstanding the differences in finger sizes, round, square or bevelled sides, or design impressed upon them.

45 From the foregoing, it will be seen that a simple device for this purpose has been disclosed in the preferred form of its em-

bodiment, but it is not desired to restrict the details to the exact construction shown, it being obvious that changes, not involving the exercise of invention, may be made without conflicting with the scope of the appended claims.

Having thus described my invention, what I claim as new and desire to secure by Letters Patent, is:—

1. A ring rolling machine comprising a fixed frame, a table guided therein, said table having a pair of recessed brackets on its top, a ring arbor removably engageable in the recesses of the brackets, a master roll 65 rotatably supported above the table in register with said arbor, a link and lever device for raising the table, an eccentric on which the lever is fulcrumed, a single hand lever to adjust the eccentric, and means for calibrating the pressure exerted on a ring disposed on said arbor.

2. A ring rolling machine comprising a fixed frame, a table adjustable therein, said table having a pair of recessed brackets on its top, a ring arbor removably engageable in the recesses of the brackets, a master roll 70 rotatably supported above the table in register with said arbor, a link and lever device for raising the table, an eccentric operable in openings in said lever, a worm and gear device to rotate the eccentric, and a hand wheel whereby the link pivots may be aligned with the fulcrum of said lever.

3. A ring rolling machine comprising a fixed frame, a table adjustable vertically therein, said table having a pair of recessed brackets on its top, a ring arbor removably engageable in the recesses of the brackets, a master roll 85 rotatably supported above the table in register with said arbor, a link and lever device for raising the table, an eccentric on which the lever is fulcrumed, a hand lever to adjust the eccentric, an eccentric 90 operable in an opening of said lever, and hand operated means to actuate the last named eccentric whereby the lever may be turned upon its pivot.

This specification signed this 18th day of December, 1924.

CLIFFORD W. ALLSOPP.
